IRRIGATOR

Charles E. Ziegler, Pittsburgh, Pa., assignor to
 Clinical Supplies, Incorporated, Pittsburgh,
 Pa., a corporation of Delaware

Application March 8, 1932. Serial No. 597,494

6 Claims. (Cl. 128—239)

This invention relates to devices for irrigating the recto-colon and vaginal cavities, and particularly to irrigators provided with a valve intermediate the fluid inlet and fluid outlet, or nozzle, 5 portions.

A major object is to provide an irrigator of generally improved construction, which is capable of being sterilized without affecting its operativeness or its efficacy in irrigating the rectum, colon 10 and vagina, embodies a simple flow-controlling valve which positively prevents leakage, and is simple and easily used. Special objects are to provide irrigators for the purposes referred to which have nozzles adapted to effect spraying and 15 to prevent premature expulsion of irrigating fluid from the organs being treated.

The invention is illustrated in the accompanying drawing, of which Figs. 1 and 2 are longitudinal central sections through a recto-colon irrigator embodying the invention, showing the irrigator in closed and open positions, respectively; Fig. 3 an enlarged view of the tip portion of the irrigator shown in Figs. 1 and 2; Fig. 4 a cross sectional view taken on line IV—IV, Fig. 25 2; Fig. 5 a fragmentary longitudinal section through the tip portion of a modified embodiment; and Fig. 6 a side view, on a reduced scale, of the invention as embodied in a vaginal irrigator.

30 The irrigator provided by this invention comprises a tubular barrel and a stem mounted for movement longitudinally within the barrel. In its intermediate portion the stem is spaced annularly from the barrel by an interior collar adjacent the rear end of the barrel, with which the stem makes a fluid-tight sliding fit, and by a flange formed on the forward, or nozzle, end of the stem and adapted to move within the forward end of the barrel. The annular space thus formed 35 provides a conduit for flow of fluid through the irrigator. Fluid is supplied through an inlet formed longitudinally of the rear end of the stem and having lateral outlet ports which are positioned to be closed by the collar when the stem is 40 in its retracted position, and to be exposed within the annular space when the stem is advanced to permit flow of liquid from the barrel. In the advanced position of the stem the flange moves forwardly sufficiently to open the forward end of the 45 barrel for flow of fluid, and preferably the flange and barrel end are shaped to cooperate in effecting a spraying action in a manner presently to be described.

Having reference to Figs. 1 to 4 of the drawing, the embodiment shown comprises a tubular

barrel 1 having a collar 2 integrally formed within its rear end. Mounted within the barrel is a cylindrical stem 3 provided at its forward end with a flange 4 which moves within the forward end of barrel 1. Collar 2 and flange 4 hold the 50 stem in fixed axial position with its intermediate portion spaced from the barrel to provide an annular passage 5 for flow of fluid to the nozzle when the stem is moved to its forward or operative position. Barrel 1 and stem 3 are formed 55 of any suitable material adapted to be inert to the fluids which may be used. For example, they may be made from hard rubber, or molded from plastics of the synthetic resin type, such as the phenolformaldehyde resins. 70

A particular feature of this invention resides in the provision of a flow-controlling valve which is positive in action and whose operativeness is not affected by the use of hot sterilizing liquids. For this purpose a nipple 6 of non-corrodible 75 metal, such as aluminum alloy, is connected to the rear end of the stem. The nipple is provided with a relatively short longitudinal fluid inlet bore 7 having at its forward end a plurality of lateral outlet ports 8 which are closed by 80 collar 2 when the stem is in the retracted position shown in Fig. 1. The rear end of the stem is connected to a fluid source, for example by means of tubular nipple 9 connected at opposite 85 ends to nipple 6 and by rubber tubing 10 to a liquid container, not shown. Nipple 6 is connected to stem 3 in any suitable manner, as by cooperating screw threads 11, and it makes a fluid-tight sliding fit in collar 2, which may be, 90 and preferably is, accomplished by grinding in.

Flange 4 is of such length and outlet ports 8 are so positioned that when the stem is moved to the forward position (Fig. 2), fluid flow is established from outlets 8, through annular passage 5, and outwardly from the nozzle formed by flange 4 and the forward end of the barrel. By this construction the rear end of the irrigator embodies a simple and efficient valve actuated solely by movement of the stem and having no other moving parts. The nipple is not affected 95 by sterilizing operations, and resists wear, so that it is always effective. Although a metal nipple is preferred, this portion of the stem may be formed of other materials adapted to withstand 100 service and confer these benefits.

The nozzle may be formed by shaping flange 4 in any appropriate manner, for example in the form shown at 4a, Fig. 5, which permits simple flow from the nozzle. Most suitably, however, the flange is constructed to cooperate with the 110

tip of the barrel to produce a spraying effect. This is accomplished in the embodiment shown in Figs. 1 to 4 by forming an inward chamfer 12 on the forward end of the barrel, and by providing a plurality of grooves at the rear of flange 4 to cause the fluid to flow from the nozzle in a plurality of streams. Preferably this is accomplished by providing a plurality of longitudinal ribs 13 which slope downwardly and rearwardly from the rear end of the flange to form intermediate fluid-carrying grooves 14. The ribs are positioned so that the flange closes the nozzle when the stem is retracted, and so that in the maximum forward movement of the stem the forward ends of the grooves are just exposed opposite chamfer 12, so that fluid flows in a plurality of streams forced against chamfer 12. Flange 4 merely fits the barrel neatly enough to direct the fluid through the grooves, a fluid-tight fit at this point being unnecessary because actual fluid flow is controlled by the valve at the rear end of the irrigator.

Preferably the forward end of the stem terminates in an external offset tip 15 of such shape as to assist in inserting the nozzle into the organ to be irrigated. The rear or offset face 16 of this tip acts as a stop to restrict rearward movement of the stem, as shown in Fig. 1, and face 16a of nipple 9 acts as a stop to limit forward movement, as seen in Fig. 2.

The irrigator described is adapted for either recto-colon or vaginal irrigation. Preferably the rear end of the barrel is provided with a lateral guard shaped to conform to the anatomy of the parts surrounding the organ to be treated, to seal the organ when the irrigator is in place, and to keep the fluid within the organ during treatment, and thus to prevent premature expulsion of the fluid. In the case of recto-colon irrigators the guard is preferably of the ovoid peripheral contour and saddle-shaped section indicated at 17, Figs. 1, 2 and 4. For vaginal irrigators the guard may be of the same peripheral contour, but of generally conical section, as shown at 17a, Fig. 6. Likewise, in vaginal irrigators the external tip is preferably shorter and blunter than in the case of recto-colon tips, as seen at 15a, Fig. 6.

The irrigator provided by this invention may be used for any purpose requiring instillation of fluid into the rectal or vaginal regions, as will be understood by those skilled in the art. Thus it may be used for flushing the colon or vagina, to medicate the vagina, to introduce drugs into the system where their retention by the stomach is difficult, to apply heat to the female pelvic organs and to the prostate or seminal vesicles of the male, or for other similar purposes. For recto-colon irrigation the patient will preferably be either in an erect or a recumbent position, while for vaginal irrigation the recumbent position is most suitable.

The irrigator with the stem retracted to close the valve, as shown in Fig. 1, is inserted into the cavity with guard 17 in loose contact with the external anatomy. The stem is then moved forwardly to open the valve, as shown in Fig. 2, to establish flow of fluid through the irrigator. When the flow of liquid into the organ has expelled any air which it contains, the guard is pressed tightly against the parts to seal the organ against leakage. At the end of the injection the stem is again retracted to close the valve, thus cutting off flow of the fluid and similarly preventing back-flow through the irrigator. If

an extended treatment is desired, as in applying heat or effecting antisepsis, the fluid may be retained in the organ for any desired length of time, the shield acting to prevent leakage and premature expulsion of the irrigating liquid. The shield also acts to prevent soiling of the hands upon withdrawal of the irrigator.

The irrigator provided by the invention also embodies various constructional advantages in addition to the operative features just indicated. Its simplicity renders it relatively inexpensive, and insures durability. It may be cleaned and sterilized readily by removing nipple 9 and withdrawing stem 3 from the forward end of the barrel. The valve is sturdy and does not wear in use or become warped upon being sterilized in boiling liquid. A further advantage is that the grooves in the spray head are protected by the undercut edge of the barrel so that in giving a clyster they do not become clogged by the bowel contents. Other features will be recognized by those skilled in the art.

According to the provisions of the patent statutes, I have explained the principle of my invention and have described what I now consider to represent its best embodiment. However, I desire to have it understood that, within the scope of the appended claims, the invention may be practiced otherwise than as specifically described.

I claim:

1. A recto-colon and vaginal irrigator comprising a tubular barrel having an internal collar at its rear end, and a stem mounted for push-pull longitudinal quick action movement in the barrel with its rear end making a slideable fluid-tight fit in said collar and provided at its forward end with a flange slidably fitting within the forward end of the barrel, the stem being solid from its forward end rearwardly throughout the major portion of its length, the rear end of the stem being provided with a longitudinal fluid inlet bore having a plurality of lateral outlet ports positioned to be closed by said collar when the stem is in retracted position, said collar and flange holding the intermediate portion of the stem spaced annularly from the barrel for flow of fluid when the stem is in its forward position.

2. A recto-colon and vaginal irrigator comprising a tubular barrel having an internal collar at its rear end, and a stem mounted for longitudinal movement in the barrel with its rear end making a slideable fluid-tight fit in said collar and provided at its forward end with a flange slidably fitting within the forward end of the barrel and terminating in an external offset tip, the stem being solid from its forward end rearwardly throughout the major portion of its length, the rear end of the stem being provided with flow-controlling valve including a fluid inlet bore extending longitudinally of the stem and having a plurality of lateral outlet ports positioned to be closed by said collar when the stem is in retracted position, and the barrel being provided at its rear end with a shield shaped to conform to the anatomy of the body parts, said collar and flange holding the intermediate portion of the stem spaced annularly from the barrel for fluid when the stem is in its forward position.

3. A recto-colon and vaginal irrigator comprising a tubular barrel having an internal collar at its rear end, and a stem mounted for longitudinal movement in the barrel with its rear end making a slideable fluid-tight fit in said collar and provided at its forward end with a flange slidably fitting within the forward end of the

- barrel, the stem being solid from its forward end rearwardly throughout the major portion of its length, said collar and flange holding the intermediate portion of the stem spaced annularly 5 from the barrel, the rear end of the stem being provided with a longitudinal fluid inlet bore having a plurality of lateral outlet ports positioned to be closed by said collar when the stem is in retracted position, and the rear end of said flange 10 being provided with a plurality of grooves positioned to have only their extreme outer ends exposed in the forward position of the stem, flow of fluid through the irrigator being established by moving the stem forwardly in the barrel.
- 15 4. A recto-colon and vaginal irrigator comprising a tubular barrel provided at its rear end with an internal collar and having its forward end chamfered inwardly, and a stem mounted for longitudinal movement in said barrel with its rear 20 end making a slideable fluid-tight fit in said collar and provided with a longitudinal fluid inlet bore having a plurality of lateral outlet ports positioned to be closed by said collar when the stem is in retracted position, the stem being solid from 25 its forward end rearwardly throughout the major portion of its length, the forward end of the stem being provided with a spray head formed by a flange slidably fitting the forward end of the barrel and terminating at its rear end in a plurality of longitudinal ribs spaced peripherally about the stem and forming intermediate fluid-carrying grooves, said collar and shoulder holding the stem spaced annularly from the barrel in fixed axial position, and the stem being moved forwardly to permit fluid to escape in a plurality of streams from said grooves directly opposite said chamfer. 30
5. A recto-colon and vaginal irrigator comprising a tubular barrel having adjacent its rear end an external shield shaped to conform to the anatomy of the body parts and an internal collar, the forward end of the barrel being chamfered inwardly, and a stem mounted for longitudinal movement in said barrel with its rear end making a slideable fluid-tight fit in said collar and provided with a longitudinal fluid inlet bore having a plurality of outlet ports positioned to be closed by said collar when the stem is in retracted position, the stem being solid from its forward end rearwardly throughout the major portion of its length, the forward end of the stem being provided with a spray head formed by a flange slidably fitting the forward end of the barrel and terminating at its rear end in a plurality of longitudinal ribs spaced peripherally about the stem and forming intermediate fluid-carrying grooves, said collar and shoulder holding the stem spaced annularly from the barrel in fixed axial position, and the stem being moved forwardly to establish flow of fluid through the barrel with the outer ends of said grooves directly opposite said chamfer. 35
6. A recto-colon and vaginal irrigator comprising a tubular barrel having an internal collar at its rear end, a stem mounted for push-pull longitudinal quick action movement in the barrel and provided at its forward end with a flange making a sliding fit within said barrel, the stem being solid from its forward end rearwardly throughout the major portion of its length, and a flow-controlling valve at the rear end of said stem including a non-corrodible, non-warping member connected to the rear end of the stem and making a sliding fluid-tight fit with said collar, said member having a longitudinal fluid inlet bore having lateral outlet ports positioned to be closed by said collar when the stem is in retracted position, said collar and flange holding the intermediate portion of the stem spaced annularly from the barrel for flow of fluid when the stem is moved to its forward position. 40
